J. S. RAYNOR

CLIP FOR FASTENING METAL LATHS

Filed Sept. 23, 1926

INVENTOR

John S. Raynor
By W. M. Williamson, Atty.

UNITED STATES PATENT OFFICE.

JOHN S. RAYNOR, OF PHILADELPHIA, PENNSYLVANIA.

CLIP FOR FASTENING METAL LATHS.

Original application filed March 17, 1925, Serial No. 16,098. Divided and this application filed September 23, 1926. Serial No. 137,231.

My invention relates to new and useful improvements in a clip for fastening metal laths, such as expanded or woven wire laths, to plasterer's steel furring irons or bars, and 5 has for its primary object to provide a device which is particularly adapted for use in connection with furring irons or bars of different cross sectional shapes.

Another object of the invention is to provide 10 a simple and inexpensive clip having a high degree of efficiency by holding the laths snug against the furring bars throughout their lengths.

A further object of this invention is to 15 provide a clip which, when in use, will lock the preceding one and be locked by the succeeding one so that by locking or fastening the last clip of a series all the clips of said series will be held securely in position.

20 With these ends in view, this invention consists in the details of construction and combination of elements hereinafter set forth and then specifically designated by the claims.

25 In order that those skilled in the art to which this invention appertains, may understand how to make and use the same, I will describe its construction in detail, referring by numerals to the accompanying drawings 30 forming a part of this application, in which:—

Fig. 1, is a perspective view of a portion of a steel furring iron or bar and a wire lath attached thereto by clips embodying my 35 invention.

Fig. 2 is a perspective view of one of the clips having a shape particularly adapted for use with furring bars of rectangular cross section.

40 Fig. 3, is a similar view of a clip designed for use with bars having an arcuate circumference.

Fig. 4, is an enlarged end view of the clip shown in Fig. 2.

45 Fig. 5, is a similar view of the clip shown in Fig. 3.

In carrying out my invention as herein embodied 5 represents a furring iron or bar which is generally used in present day 50 building construction to support metal laths or lathing 6 and the plaster carried thereby, it being understood that the metal lath is of expanded or woven formation.

To securely fasten the metal lath to the furring iron or bar, I provide a clip constructed of round, square or flat sections of metal rod or wire fashioned to produce a body 7 with a locking leg 8 projecting from one end thereof at substantially right angles thereto and comprising a limb 9 from 55 which projects a horizontal intermediate arm 10 and from the latter projects a down-turned branch 11 parallel to the limb 9, said branch 11 terminating in an outwardly 60 extending toe 12 in a projected line parallel 65 with the body 7.

At the opposite end of the body is formed a stay leg 13 comprising a limb 14, substantially at right angles to said body and from this limb projects a horizontal section 15, 70 substantially at right angles to the limb 14.

The above description relates particularly to the clip shown in Fig. 2, but by making the part 16 between the limb 9 and the branch 11 of curved formation, as shown 75 in Figs. 1, 3 and 5, a locking element or leg is provided which is particularly adapted for use in connection with furring irons or bars of arcuate formation while in other respects the clips shown in Figs. 1 and 3 80 are identical with the one shown in Fig. 2.

In practice the metal lath 6 is temporarily secured against the furring iron or bar 5 and then permanently fastened by means of a series of the clips which are attached, 85 one at a time, and to place said clips in position one of them is first manipulated so that the locking element is inserted through an opening in the lath on one side of the furring bar and then turned so that the portion 10 or 16 lies across the furring bar with the toe 12 lying against the inner surface of the lath. The stay end of the clip is then drawn over until it takes a position on the side of the furring bar opposite to 90 that of the limb 9 so that the body 7 assumes a position diagonal to the axis of the furring bar and the stay end is then inserted through an opening in the lath and moved over until the horizontal portion or section 15 engages that side of the furring bar opposite the lath.

The locking end of the succeeding clip is then inserted through an opening in the lath beyond the stay end of the preceding 105 clip and when properly positioned as above

described the toe of the locking element of said succeeding clip will engage the limb of the stay leg of the preceding clip and thereby lock it against displacement and rotation.

5 A series of these clips is placed in position in this manner until the lath is held firmly against the furring bar and the last one of the clips, or more particularly the stay end of said last clip, is secured in place 10 by a suitable tie 17, such as a piece of wire looped about the body of the clip and the furring bar.

15 Of course I do not wish to be limited to the exact details of construction as herein shown as these may be varied within the limits of the appended claims without departing from the spirit of my invention.

Having thus fully described my invention, what I claim as new and useful is:—

20 1. As a new article of manufacture, a clip fashioned from a section of wire like material to provide a body, a locking leg projecting from one end at substantially right angles thereto and comprising a limb, an arm projecting from said limb, a down-turned branch extending from said arm and an outturned toe projecting from the branch, a stay leg projecting from the opposite end 25 of the body at substantially right angles thereto and comprising a limb and a horizontal portion projecting from said limb

at substantially right angles to the latter.

2. A clip for securing metal laths to furring bars consisting of a section of suitable metal so fashioned as to form a body, a stay element at one end of the body for engagement with the furring bar, and a locking element at the opposite end of the body for embracing the furring bar, said locking element including an outturned toe for cooperation with a lath to prevent rotation of the clip and coacting with the stay element of an adjacent clip to assist in holding the latter in place. 35

3. A wire lath clip comprising a body, a limb projecting from one end of the body, an arm projecting from said limb, a branch projecting from the arm parallel with the limb, a toe projecting outwardly from the branch, another limb projecting from the 50 other end of the body, and a horizontal portion projecting from the last mentioned limb. 40

4. A lath clip including a body, a substantially L-shaped stay leg at one end of the body, a substantially U-shaped locking element at the other end of the body, and an outwardly projecting toe extending from the locking element. 45

55 In testimony whereof, I have hereunto affixed my signature.

JOHN S. RAYNOR.
